Primary Examiner — George J Ulsh*Assistant Examiner* — Kathryn Elizabeth Zieno(74) *Attorney, Agent, or Firm* — Kinney & Lange, P.A.(57) **CLAIM**

The ornamental design for a spray gun as shown and described.

DESCRIPTION

FIG. 1 is a first isometric view of a spray gun;
FIG. 2 is a second isometric view of the spray gun;
FIG. 3 is a right side view of the spray gun;
FIG. 4 is a left side view of the spray gun;
FIG. 5 is a front elevational view of the spray gun;
FIG. 6 is a rear elevational view of the spray gun;
FIG. 7 is a top plan view of the spray gun; and,
FIG. 8 is a bottom plan view of the spray gun.

The broken lines in the Figures represent portions of a spray gun and form no part of the claimed design.
